UNITED STATES PATENT OFFICE.

WILLARD A. DUNHAM, OF WEYMOUTH, MASSACHUSETTS.

LACING-HOOK.

SPECIFICATION forming part of Letters Patent No. 707,090, dated August 19, 1902.

Application filed March 5, 1902. Serial No. 96,767. (No model.)

To all whom it may concern:

Be it known that I, WILLARD A. DUNHAM, of Weymouth, in the county of Norfolk and State of Massachusetts, have invented a new and useful Improvement in Lacing-Hooks More Especially Adapted for Use in Lacing Shoes, Gloves, and the Like, of which the following is a specification.

My invention relates to an improvement upon the ordinary lacing-hook whereby it may be made to be used both as a lacing-hook and also as a fastener for the ends of the lacing.

My invention consists in a lacing-hook which may be used in the same way that the ordinary hook is used to receive the lacing as it is zigzagged from one hook to the other across the opening of the shoe, but which may also by reason of its peculiar construction in addition receive and bind the end of the lacing, so that it need not be tied.

My invention will be understood by reference to the drawings, in which—

Figure 1 is a plan showing four of my lacing-hooks attached near two edges of the opening in a shoe, Fig. 2 being a section on line 2 2 of Fig. 1, and Fig. 3 a section on line 3 3 of Fig. 1, the lacing being outlined in Figs. 2 and 3. Fig. 4 is a plan of a partially-made lacing-hook, showing the blank for the hook proper.

A is the attaching member of the device, which comprises, preferably, an eyelet, as shown, although it may be made with prongs or in any other desirable way. From this attaching member extends the tongue B, like that of the ordinary lacing-hook. So far my device is identical in appearance with the ordinary lacing-hook, such as is well known in the market. In addition, however, my hook has a second tongue C, which, as shown, (see especially Fig. 4,) is cut from the central portion of the tongue B, but is bent down to form two chambers, one, b, between the attaching member and the lower tongue C and the other, b', between the lower tongue C and the upper tongue B. The space b, between the attaching member A and the tongue C, is large enough to hold the shoe-lacing, and the space b', between the tongue C and the tongue B, is also large enough to allow the lacing to be given a turn about the de-

vice and to be entered into the hook again in the space b', between these two tongues. The tongue C has spring enough to allow it to give slightly, as may be required by the thickness of the lacing. This will be understood from Fig. 1, where D indicates the lacing, which in the ordinary lacing of the hook at the top of the shoe is given a second turn about the hook, its end passing between the two tongues and there being jammed in place.

While my lacing-hook may be made of wire bent into the required shape, I prefer to make it of sheet metal, and in Fig. 4 I show a blank from which it may be made, the eyelet being shown as already formed and the other parts being lettered as in the other views, E being the shank which joins the tongues with the eyelet, and C' being slits which separate the tongue B from the tongue C. In the finished hook the shank E may be rounded or flat, as thought best, and the finished tongue B may be rounded or flat, according to the taste. I have shown the slits C' extending to the extreme edge of the blank, so that the tongue B is forked, as I prefer such construction; but my invention relates to a device in which there are, in effect, two tongues, which are bent substantially at right angles to the shank, the one under the other, so that the upper one forms, as it were, a protection or cover for the lower.

The advantages of this hook will be apparent when it is considered that it may be made to resemble in finish the hook now so well known either by a coating of celluloid, varnish, or any other finish, so that it will have no appearance of novelty to the purchaser, that it may be attached to the shoe and used either as an intermediate hook between the ordinary eyelets and the top of the shoe in precisely the way in which the ordinary hook is at present used or as a fastening-hook at the top of the shoe. Another advantage of this construction lies in the fact that where, as is sometimes the case, a shoe-lacing breaks it may be temporarily used by giving it a turn about the last hook which it will reach and in the same way giving to the detached end a couple of turns around the same hook, after which the usual lacing process may be continued.

My device can be made at no greater ex-

pense than the ordinary hook, for the reason that all that is necessary is to change slightly the shape of the cutting and forming dies, so that they will cut out a blank having the two tongues and will bend this blank in the manner shown, so that each tongue can be effective. It is apparent, however, that this invention is not limited to a fastener made of sheet metal and cut in the manner described, for it comprises a lacing-hook having an attaching member and two tongues forming two chambers separated from each other by the middle tongue, and, moreover, this middle tongue may be bent slightly, as at *c*, so as to form a rib to assist in holding the second turn of the lacing in place. It is also evident that this device may be used as well upon gloves or in other like places as upon shoes.

20 What I claim as my invention is—

1. The one-piece lacing-hook above described, comprising an attaching member, a shank and two tongues integral therewith, and projecting laterally from the same side of said shank, one *B*, of said tongues forming the head of said hook, and the other tongue *C* being stamped out of said tongue *B*, and both tongues projecting laterally from the same side of said shank, the tongue *B* lying over the tongue *C* and forming a protection therefor, and the tongue *C* being bent down somewhat to divide the space between

the tongue *B* and the attaching member into two chambers, one over the other and both over the attaching member, each chamber 35 being of sufficient size to receive a lacing-cord, as and for the purposes described.

2. A blank for a lacing-hook comprising a portion to form an attaching member, a portion extending laterally to form a shank, and 40 a portion beyond said shank to form a lacing-receiving member, said attaching member, said shank portion and said lacing-receiving portion being located in the same straight line, said lacing-receiving portion being provided with two slits extending in a straight 45 line from its extreme edge toward said attaching member parallel with the length of the blank, whereby said lacing-receiving member may consist of two tongues, one of 50 said tongues being forked, the other tongue being formed from the portion of the blank between said forks, the two tongues being capable of being bent, the one under the other, to form two parallel coextensive chambers, the one over the other and both directly over said attaching member, as described.

In testimony whereof I hereunto set my name this 26th day February, 1902.

WILLARD A. DUNHAM.
